UNITED STATES PATENT OFFICE.

ALBERT F. FIFIELD, OF NEWARK, NEW JERSEY, ASSIGNOR TO THE SINGER MANUFACTURING COMPANY, OF ELIZABETH, NEW JERSEY, A CORPORATION OF NEW JERSEY.

STOP-MOTION MECHANISM.

Application filed December 20, 1919. Serial No. 346,346.

To all whom it may concern:

Be it known that I, ALBERT F. FIFIELD, a citizen of the United States, residing at Newark, in the county of Essex and State of New Jersey, have invented certain new and useful Improvements in Stop-Motion Mechanisms, of which the following is a specification, reference being had therein to the accompanying drawings.

10 This invention relates to an improvement in stop-motion mechanism for sewing machines and particularly to stop mechanism for machines for sewing on buttons, barring, tacking or similar operations although 15 it is by no means confined to use with this type of machine.

Machines of this type have previously been operated at the relatively low speed of 1000 or 1200 stitches per minute. In my co-pending application Serial No. 294,034, filed May 1, 1919, I have disclosed a machine of this type adapted to be operated at a higher speed and an object of this invention is to provide an improved automatic brake for 25 the stop-motion which will lessen the shock of stopping at the high speed employed, reduce wear and tear on the stop-motion mechanism and quickly reduce the speed so that the thread-cutter mechanism which is 30 actuated by the stop-motion, will not act upon the thread with too great abruptness.

Another object is to provide means for regulating the action of the brake to suit different speeds.

35 This application is a division of my above mentioned copending application Serial No. 294,034, filed May 1, 1919.

In its preferred form the invention comprises a brake mechanism adapted to act 40 upon the driving pulley of the machine and connected with the stop-motion in such a way that it is applied as soon as the stop-lever is tripped but is released and reset for the next application by a shock absorbing 45 movement of the stop-lever as the machine comes to a stop. The force for applying the brake is obtained from a spring which is provided with means for varying the braking effect.

50 Referring to the accompanying drawings, Fig. 1 is a front elevation of the machine. Fig. 2 is a rear elevation of the standard and its associated mechanism. Fig. 3 is an end view from the right of Fig. 1. Fig. 4 is a

bottom plan view of the end corresponding 55 to Figs. 2 and 3. Fig. 5 is a detail horizontal section above the work-plate at the right hand end of Fig. 1, and Fig. 6 is a perspective view of the catch mechanism for the 60 brake.

The numeral 1 designates the base of the work-plate of the machine from which rises the standard 2 carrying the overhanging arm 3 with head 4. A main-shaft 5 is mounted within the arm 3 and at its rear 65 outer end carries the loose pulley 6 and a fast pulley 7. At its other end, shaft 5 has mechanism for operating the thread take-up arm and the needle. Within the standard 2 shaft 5 has a beveled gear connection with 70 a vertical shaft 7 and the latter in turn has a bevel gear connection with a rotary loop-taker shaft 8. The main-shaft 5 also carries a worm 9 meshing with the worm-wheel 10 on the transverse shaft 11 on which shaft 75 is mounted the controller cam-wheel 12, Figs. 1 and 2. A jogging work-clamp and work-support of well known form is provided, the same being indicated as a whole by the reference numeral 13. The work-support 80 is given movement transversely and longitudinally of the work-plate from the controller cam-wheel 12 through the levers 14 and 15, respectively, as disclosed in the parent application. These means are sub- 85 substantially those shown in the patents to Sullivan, No. 777,564, of December 13, 1904, and Barron, No. 1,093,241, of April 14, 1914.

A stop-lever 16 is pivotally mounted in the lug 17 on the frame for movement on an 90 axis transverse the length of the work-plate and carries a belt-shifter 18 secured near its upper end. A spring-pressed plunger 19 at the upper end of the lever is adapted, when in proper position, to engage a stopping cam 20 on the main-shaft 5 to stop the machine. The stop-lever also has a limited sidewise 95 shock absorbing movement after engaging the stopping cam, as it is pivoted on the member 21 which is mounted to turn in the lug 17. The stop-lever is held out of engagement with the stopping cam and in the position shown in Fig. 2 by means of the spring-pressed latch 22 which engages the rear side of the lever. At the close of a 100 sewing operation this latch is released by a cam-lug 23 (Fig. 1) on the inner side of the controller cam-wheel 12. The stop-motion 105

mechanism so far described is old and well known and is fully shown and described in the patent to Barron, No. 1,093,241. The coil-spring 24 is secured at one end to the 5 lower end of the stop-lever 16 and at its other end to a pin 25 projecting below the base. This spring tends to move the stop-lever to stopping position. In starting, the stop-lever is moved out of alinement with the stopping cam and into engagement with the latch 22 by means of the push-rod 26 (Figs. 1 and 4) located below the base and adapted to contact at one end with the lower end of the stop-lever. This push-rod is connected at its other end to the downwardly projecting arm 27 of a bellcrank-lever pivoted to a lug on the lower side of the base. The other arm 28 of the bellcrank-lever may be connected to a treadle or other means for 10 operating it by a chain 28'. The coil-spring 29 surrounds the push-rod and is confined between a collar 30 and a bearing lug 31 which spring tends to normally hold the push-rod out of engagement with the stop-lever. 15

Owing to the high speed employed it has been found desirable to use a brake to assist the stop-motion mechanism in stopping the machine. This brake comprises a brake-shoe 32 adapted to bear against the fast pulley 7 and pivotally connected to the upper end of a brake-lever 33 pivoted on the frame at 34. A coil-spring 35 is connected at one end to the lower end of the brake-lever and at its other end to an arm 36 projecting from a short vertical shaft 37 extending through and above the base. Above the base a finger-lever 38 provided with a thumb-screw 38' is connected to the shaft 37. The spring 35 tends to throw the brake into action and by means of the finger-lever 38 and arm 36 tension of the spring may be varied to thereby vary the action of the brake at different speeds. The 20 brake acts only between the time the stop-lever is first tripped to shift the belt and the time the shock absorbing motion of the stop-lever takes place and the following means are provided to secure this result. A 25

small contact lever 39 (Figs. 4 and 5) is pivoted at the rear of the base at 40, one end of which lever is adapted to be actuated by the lower end of the stop-lever 16 in its sidewise shock absorbing movement and the opposite end of the contact lever has a pivotal connection at 41' with a sliding bar 41 having the cam-lug 42 engaging a cam-lug 43 on the lower portion of the brake-lever. The bar 41 also has a latching projection 44 engageable by one end of a latch-lever 45 pivoted at 46 and pressed toward the projection by a coil-spring 47. The other end of the latch-lever 45 has a trip 48 pivotally connected thereto and yieldingly held in a position at substantially right angles to the lever by means of a coil-spring 49. A stop 45' on the lower side of the latch-lever 45 prevents the coil-spring 49 from pulling the trip 48 too far over. 5

The thread-cutting mechanism as described in the parent application is operated by the slide-bar 50 extending substantially the length of the machine. At its rear end the bar 50 carries a block 51 having a notch 52 entered by the reduced lower end of a lever 53 pivotally mounted at 54 on the bracket 55 secured to the frame (Figs. 2 and 3). The upper end of the lever 53 carries a cam-follower movable in a cam-groove 54 in the cam-wheel 12. The block 51 also carries the roller-stud 56 engaged by a fork-arm 57 of a bellcrank-lever fulcrumed at 58. The other arm 59 of the lever carries the plunger-pin 60 at its end which pin is pressed outwardly by a spring 61. The pin 60 is adapted to enter a recess 62 in the lower part of the stop-lever 16 just before the overthrow movement of the latter takes place. The above described means for actuating the slide-bar 50 and bellcrank-lever 57, 59 from the stop-lever and controller cam-wheel are substantially those shown in the patent to Barron, No. 1,093,241 above mentioned. 10

In operation the stop-lever 16 is shifted by the treadle-connection 28' of bellcrank-lever arm 28 which throws the belt to the fast pulley 7, moves out the lower end of the stop-lever and allows the trip 48 to slip behind it and allows the latch 22 to engage the lever 16. The brake is in ineffective position and its operating parts are disposed as shown in Fig. 5, i. e., the sliding bar 41 is latched in its extreme right hand position, its cam-lug 42 has moved out the cam-lug 43 on the brake-lever 33 against the action of the spring 35 thereby freeing the brake and the trip 48 is in position to communicate the initial stopping movement of the stopping lever 16 to the latch-lever 45 and free the latter from the projection 44 on the slide-bar 41. The stitching then proceeds in the manner usual with machines of this type. 15

At the finish of a sewing operation the needle makes several thrusts in the same hole to form tying stitches. As the needle comes down on its last reciprocation, the cam projection 23 engages the latch 22 and releases the stop-lever 16 which latter is at once acted upon by its spring and shifts the belt to the loose pulley and draws the plunger 19 into the path of the stopping cam 20. The lower end of the stop-lever pressing on the trip 48 releases the latch 45. The brake-lever spring 35 immediately throws the brake into action and as the lower end of the brake-lever moves inwardly the cam-lug 43 acts upon the cam-lug 42 forcing the slide-bar 41 to the left as viewed in Fig. 5 and the lever 120

39 to the right and in contact with the stop-lever. The main-shaft continues to turn due to its momentum and the passing of the follower on the lever 53 up the incline to the 5 projection 54' of the cam-wheel moves the slide-bar 50 connected to the cutter mechanism. The bellcrank-lever 57, 59, being also connected to the slide-bar 50 is likewise moved and its plunger-pin 60 springs into 10 the recess 62 of the stop-lever 16 as it comes into alignment therewith. Finally the plunger 19 on the stop-lever 16 comes into engagement with a projection 20' on the stop-cam 20 causing a sidewise shock absorbing movement of the stop-lever against the action of a spring-pressed plunger mounted in the boss 6. This sidewise movement is transmitted by the bellcrank-lever 57, 59, and slide-bar 50 to the thread-cutter to give it its final 15 thread-cutting movement as described in the parent application. As before stated, the means by which the sidewise movement is imparted is substantially that shown in the patent to Barron, No. 1,093,241 and forms no 20 part of my invention. As the sidewise or shock absorbing movement takes place the lower end of the stop-lever also actuates the lever 39 which latter moves the slide-bar 41 to the right and the cam-lug 42 on said bar 25 acts on the cam-lug 43 to force the lower end of the brake-lever 33 outwardly and release the brake. At the same time the latching projection 44 on the bar 41 comes in position to be engaged by the latch-lever 45 and the spring 47 urges the latch into engagement 30 with this projection. As the lower end of stop-lever 16 has moved to the left, Figs. 3, 5 and 6, in its sidewise movement the trip 48 can move outwardly along the right side 35 of the lever 16 as the right-hand end of the latch-lever 45 swings outwardly. As the stop-lever 16 swings back from its sidewise movement it moves trip 48 slightly to the right against the tension of the spring 49 40 and when the lever is reset at the beginning of the next sewing operation its lower end moves outwardly allowing spring 49 to pull trip 48 in rear of the lever again as shown in Fig. 5.

45 The present machine is capable of the relatively high speed of 1800 stitches per minute and by use of applicant's improved brake the machine is stopped without undue wear and tear on the stop-motion mechanism.

50 Having thus set forth the nature of the invention, what I claim herein is—

55 1. In a stop-motion mechanism, a stop-lever having initial and final stopping movements, a driven pulley, a spring-pressed 60 brake therefor, means normally holding the brake out of action, means actuated by the initial movement of the stop-lever whereby said holding means is released and the brake applied, and means actuated by the final 65 movement of the stop-lever whereby the

brake is thrown out and held in ineffective position.

2. In a stop-motion mechanism, a shaft having a driven pulley, a positive stop including a lever having different movements, 70 a brake for said pulley, yielding means tending to apply said brake, a spring-pressed latch for holding the brake out of action, means actuated by one movement of the lever whereby said latch is released and the brake 75 applied, and means actuated by another movement of said lever whereby the brake is released and the latch applied again.

3. In a stop-motion mechanism, a driven shaft, a positive stop therefor, a retarding 80 means for the shaft, means for locking the retarding means in ineffective position, and means for throwing said retarding means into action prior to the action of the positive stop and for throwing out and locking the 85 retarding means as the positive stop acts.

4. In a stop-motion mechanism, a driven shaft, a spring-pressed brake for said shaft, a stop-lever having a plurality of movements, a latch for holding said brake out of 90 action, means operatively associated with said lever for releasing said latch on one of the movements of the said lever, and means operatively associated with said lever for causing said latch to be set again on another 95 movement of said lever.

5. In a stop-motion mechanism, a rotary element, a friction brake-element and a positive stop-element adapted for successive engagement with said rotary element, and 100 means controlled by movement of the positive stop-element for throwing the brake-element both into and out of engagement with the rotary element as the machine is brought to rest.

6. In a stop-motion mechanism, a rotary element, a friction brake-element and a positive stop-element adapted for successive action upon said rotary element, said stop-element having a movement into stopping 110 position and a shock absorbing movement while arresting the motion of the rotary element, and means controlled by the respective movements of the positive stop element for throwing the brake-element into and out 115 of action.

7. In a stop-motion mechanism, a retarding device, a positive stop including a stop-lever having a plurality of stopping movements and a setting movement, a trip and a lever actuated by said stop-lever in its stopping movements for respectively throwing in and out of action the retarding device, and means for resetting the trip on the setting movement of the stop-lever. 120

8. In a stop-motion mechanism, a rotary element, a friction brake-element and a positive stop-element adapted for successive action upon said rotary element, and a plurality of separate elements successively act- 125 130

ed upon by said stop-element for throwing the brake-element into and out of action.

9. In a stop-motion mechanism, a positive stop, a retarding device, an actuating connection adapted to be interposed between the two at the beginning of a work-cycle, means for tripping the positive stop into action at the close of a work-cycle, to thereby apply the retarding device, and means actuated by 10 the positive stop at the end of the work-cycle for throwing out of action the retarding device.

10. In a stop-motion mechanism, a shaft having loose and fast pulleys and a positive stop-member thereon, a brake for retarding the rotation of said shaft, trip controlled means for engaging said stop-member and shifting the belt from the fast to the loose pulley, and means controlled by 20 said trip-controlled means for shifting said brake into and out of action prior to the completion of the action of the positive stop.

11. In a stop-motion mechanism, a shaft, 25 a positive stop therefor having a movement to stopping position and a shock absorbing movement, a brake for said shaft, means for putting said positive stop and brake into action, and means actuated by the overthrow movement for releasing said brake.

12. In a stop-motion mechanism, a shaft, a positive stop therefor having a movement to stopping position and a shock absorbing movement, a brake for said shaft, spring 35 means for actuating said stop and brake, means controlled by the revolution of said shaft for releasing said first means, and means actuated by the shock absorbing movement for withdrawing said brake from 40 action.

13. In a stop-motion mechanism, a shaft, a positive stop therefor, a brake for said shaft, unitary means for tripping said stop and brake into action, automatic means for 45 releasing said brake, and manual means for releasing said stop.

14. In a stop-motion mechanism, a shaft, a positive stop therefor, a latch for holding the same out of action, a brake for said shaft, a latch for holding said brake out of action, means actuated by the movement of the shaft for tripping said first latch, and means actuated by the movement of the stop 50 for tripping said second latch.

15. In a stop-motion mechanism, a shaft, a positive stop therefor having stopping and shock absorbing movements, a latch for holding the stop out of action, a brake for said shaft, a latch for holding said brake 55 out of action, means actuated by the movement of the shaft for releasing said first latch, means actuated by the stopping movement to release said second latch, and means actuated by the shock absorbing movement

for throwing said brake out of action and 65 into engagement with its latch.

16. In a stop-motion mechanism, a shaft, a positive stop therefor having stopping, shock absorbing and setting movements, a 70 brake for said shaft, a latch for holding said brake out of action having a trip for releasing it actuated by the stop in its stopping movement, means actuated by the stop shock absorbing movement to again engage the 75 brake by its latch, and means governed by the setting movement of the stop for setting the trip.

17. In a stop-motion mechanism, a shaft having a positive stop member thereon, a stop-lever having a plurality of movements, 80 a spring actuated brake for said shaft, brake tripping means controlled by one of the movements of the stop-lever for rendering the brake effective, and brake resetting means actuated by another movement of the 85 stop-lever prior to the complete stopping of the shaft.

18. In a stop-motion mechanism, a shaft, a positive stop-member thereon, a brake for 90 said shaft, a stop-lever having movements longitudinally and transversely of said shaft, one of which movements engages the stop-lever with the stop-member and causes the brake to act, and means controlled by the other movement for releasing the brake. 95

19. In a stop-motion mechanism, a shaft, a positive stop-member thereon, a spring-pressed brake for said shaft, means for holding said brake out of action, a stop-lever having movements on axes at right angles to 100 each other, one of which movements engages the stop-lever with the stop-member and releases said holding means, and means actuated by the stop on its other movement for releasing the brake and engaging it with 105 said holding means.

20. In a stop-motion mechanism, a stop-lever having a plurality of stopping movements, a shaft, a brake therefor, means normally holding the brake in ineffective position, means actuated by the initial movement of the stop-lever for releasing said holding means, and means actuated by a succeeding movement of the stop-lever for returning the brake to ineffective position. 110

21. In a stop-motion mechanism, a shaft, a normally ineffective brake therefor, a positive stop for said shaft having a movement to stopping position and a second movement as the shaft comes to rest, means controlled by the first movement of the stop for applying the brake, and means controlled by its second movement for rendering the brake ineffective. 115

In testimony whereof, I have signed my 125 name to this specification.

ALBERT F. FIFIELD.
